[57] CLAIM

The ornamental design for a container for toys, as shown and described.

DESCRIPTION

FIG. 1 is a perspective view of a container for toys shown in a closed position;

FIG. 2 is a top view thereof;

FIG. 3 is a front view thereof, which is also identical to a rear view thereof;

FIG. 4 is a side view thereof, which is also identical to the other side view thereof;

FIG. 5 is a perspective view of the container with its flaps partially open with their locking member removed therefrom.

FIG. 6 is a perspective view of the container without its locking member and its flaps in a closed position; and,

FIG. 7 is a top view thereof.
